COMPRESSOR PISTON RING

Andrew Kalitinsky, Eagleville, Conn., assignor to
 United Aircraft Corporation, East Hartford,
 Conn., a corporation of Delaware

Application January 30, 1945, Serial No. 575,339

14 Claims. (Cl. 309—4)

1
 This invention relates to a compressor piston construction, particularly adapted for use in a free-piston unit.

When an engine and compressor unit is used in pumping media of different densities the change in density may be compensated for by providing ports in the wall of the compressor. The ports are opened or closed for adjusting the effective volume of the compressor as described in the copending Kalitinsky application, Serial No. 550,884, filed August 23, 1944, now Patent No. 2,441,272, May 11, 1948. For effective sealing, the piston rings on the compressor piston must be more widely spaced than the axial dimension of each port and the thickness of the piston must be enough greater than this dimension to receive and support the rings. A feature of this invention is a piston having a single piston ring on its periphery, the width of which is greater than the axial dimension of the ports. Another feature is the formation of integral ribs on the periphery of the ring the spacing of the ribs being greater than the axial dimension of the port.

In free-piston units the mass of the reciprocating piston assembly controls the frequency so that for high frequency operation a low piston mass is necessary. A feature of this invention is a piston ring construction for the compressor piston which will be substantially as wide as the piston and will permit the use of a relatively thin light weight piston. Another feature is the arrangement of the ring to minimize leakage past it.

Other objects and advantages will be apparent from the specification and claims, and from the accompanying drawings which illustrate an embodiment of the invention.

Fig. 1 is a sectional view through a free-piston unit.

Fig. 2 is a fragmentary sectional view on a larger scale of the ring for the compressor piston.

Fig. 3 is a fragmentary view of the periphery of the ring.

The unit in which the piston construction is shown includes an engine cylinder 10 having reciprocating pistons 12 and 14 to which the compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into the engine cylinder through one or more nozzles 32. Air compressed

2
 in the air spring cylinders on the power stroke returns the piston assemblies. The assemblies are always maintained at equal distances from the center of the engine cylinder by a linkage, not shown.

Intake manifold 42 which extends around the compressor and engine cylinders conducts air to intake valves 44 in the heads of the compressor cylinders through which air alternately enters opposite ends of the cylinders. The compressed air leaves the cylinders through discharge valves 46 also at opposite ends of the compressor cylinders and passes into a central scavenging duct 48 and end chambers 50 and 52. These chambers may be interconnected by a scavenging manifold, not shown.

Compressed gas from the scavenging chambers enters engine ports 54 and 56 which are uncovered by pistons 12 and 14 at the end of the power stroke, thereby permitting air to be blown through the engine cylinder. Gas in the engine cylinders is discharged through exhaust ports 58 into exhaust manifold 60.

Each compressor cylinder may have a number of axially spaced rows of spill ports 62 to permit discharge of air without compression from the cylinder. Each row of ports may be individually controlled by a band 64, Fig. 2, extending around the cylinder between projecting ribs 66 extending from the cylinder. Each band has a number of openings 68 corresponding in spacing to the ports so that by angular motion of the band the openings 68 may be aligned with the ports 62. This arrangement is described in detail in the copending Kalitinsky application, above referred to.

As shown in Fig. 2, the compressor piston 18 has a tongue 70 on its periphery engaging in groove 72 in a wide piston ring 74 which extends around the cylinder and is split so that it expands by its resiliency into engagement with the wall of cylinder 22. The outer side surfaces 76 and 78 of the piston ring are beveled to conform to the taper of the compressor piston and to form continuations of the side walls of the piston.

On the periphery of the piston ring may be formed integral ribs 80 and 82 which are at the outer edges of the ring and which, as shown, are spaced apart a distance greater than the axial dimension of the spill port 62.

As shown in Fig. 3, the split 84 in the piston ring is substantially Z-shaped, with the parallel bar elements of the Z spaced apart a distance greater than the thickness of tongue 70. By this

arrangement leakage of air past the split in the piston ring is reduced to a minimum.

It is to be understood that the invention is not limited to the specific embodiment herein illustrated and described, but may be used in other ways without departure from its spirit as defined by the following claims.

I claim:

1. A compressor cylinder having a number of ports in its outer wall, and a piston in said cylinder, in combination with a single piston ring on the periphery of the piston and engaging with the cylinder wall, said ring having an effective width greater than the diameter of the ports.

2. A compressor cylinder having a number of ports in its outer wall, and a piston in said cylinder, in combination with a single piston ring on the periphery of the piston, said ring having integral cylinder engaging ribs on its periphery.

3. A compressor cylinder having a number of ports in its outer wall, and a piston in said cylinder, in combination with a single piston ring on the periphery of the piston, said ring having integral cylinder engaging ribs on its periphery, the spacing of which is greater than the axial dimension of the ports.

4. A compressor cylinder having a number of ports in its outer wall, and a piston in said cylinder, in combination with a single piston ring on the periphery of the piston and engaging with the cylinder wall, the ring being substantially as wide as the thickness of the piston and at least as wide as the axial dimension of the ports in the cylinder wall.

5. A compressor cylinder having a number of ports in its outer wall, and a piston in said cylinder, in combination with a single piston ring on the periphery of the piston, the ring being substantially as wide as the thickness of the piston, and having integral ribs on its outer periphery closely adjacent to the side surfaces of the ring.

6. A ring for a compressor piston having a width substantially equal to that of the piston, and having ribs on its periphery, said ring being split and having means on its inner surface for engagement with the piston to retain the ring in place on the piston.

7. A ring for a compressor piston having a width substantially equal to that of the piston, and having ribs on its periphery, said ring being split and having a groove on its inner surface by which it is located on the periphery of the piston.

8. A ring for a compressor piston having a width substantially equal to that of the piston, and having ribs on its periphery, said ring being split to permit expansion, the split being Z-shaped.

9. A piston having its outer surfaces tapering toward the periphery, in combination with a split piston ring on the periphery, the side surfaces of the ring tapering and forming continuations of the piston surfaces.

10. A piston having its outer surfaces tapering

toward the periphery, in combination with a split piston ring on the periphery, the side surfaces of the ring forming continuations of the piston surfaces, said ring having integral ribs on the periphery.

11. A piston having its outer surfaces tapering toward the periphery, in combination with a split piston ring on the periphery, the side surfaces of the ring forming continuations of the piston surfaces, said ring having integral ribs on the periphery, the split in the ring being Z-shaped to minimize leakage.

12. A piston having a ring engaging means on its periphery, and a piston ring substantially equal in width with the thickness of the piston and having means on its inner periphery cooperating with the ring engaging means, said ring having integral ribs on its outer periphery for engagement with a cylinder wall.

13. A piston having a rib on its periphery, and a piston ring substantially equal in width to the thickness of the piston, and having a groove in its inner periphery cooperating with the rib on the piston, said ring being split and having integral ribs on its outer periphery adjacent to the side surfaces of the ring for engagement with the cylinder wall.

14. A piston having a rib on its periphery, and a piston ring substantially equal in width to the thickness of the piston, and having a groove in its inner periphery cooperating with the rib on the piston, said ring being split and having integral ribs on its outer periphery adjacent to the side surfaces of the ring for engagement with the cylinder wall, the split in the ring being Z-shaped with the bar elements of the Z being parallel to and spaced from the side walls of the groove.
